CLAIM

The ornamental design for an angle head, as shown and described.

DESCRIPTION

FIG. 1 is a front, top, left side perspective view of an angle head showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view thereof; and,

FIG. 8 is a rear, top, left side perspective view thereof.

The broken line showing of an angle head is for the purpose of illustrating portions of the article and forms no part of the claimed design.
